FLUID OPERATED THROTTLE ACTUATOR
Homer V. Krautwurst and Edward H. Seidewand, Rochester, N.Y., assignors to General Motors Corporation, Detroit, Mich., a corporation of Delaware
Filed Sept. 5, 1963, Ser. No. 306,830
4 Claims. (Cl. 60—54.5)

This invention relates to means for retarding the closure of a hydraulically actuated internal combustion engine throttle valve.

Since an engine connected to an automatic transmission has a tendency to stall upon a sudden closure of the throttle valve, it has become common to provide most carburetors with a device which will slow the final closing movement of the throttle valve and reduce the stalling tendency. The present invention provides a novel means to slow the throttle valve closure.

The present invention constitutes an improvement over a prior hydraulic actuator for an internal combustion engine throttle valve wherein the engine operator controls a master cylinder at one end of a hydraulic circuit. The master cylinder creates pressure variations which are transmitted through the circuit to a servo. The servo opens the throttle valve in response to pressure increases.

Included in the servo of this prior actuator is a valve which retards pressure transmittal by fluid displacement in a throttle valve closing direction after predetermined throttle valve closure. By retarding the fluid flow, the rate of closing of the throttle valve, and thus the stalling tendency, is reduced.

In the present invention, the plunger which acts as a connecting link between the diaphragm in the servo and the throttle lever is constructed to abut against the diaphragm instead of being secured to the diaphragm as has been formerly done. The plunger, instead of the diaphragm, is biased in the throttle valve closing direction. This construction permits the throttle valve to be actuated by a mechanic at the carburetor end of the linkage, as is often the case, without creating a vacuum against the diaphragm. By preventing the creation of a vacuum, the present invention prevents buckling of the diaphragm and promotes longer life thereof.

In the present invention the retarding valve is supported independently of the diaphragm, and improper alignment of the valve by the diaphragm is thus avoided.

By providing an independent plunger and valve support, the present invention also allows the diaphragm to be formed without an aperture, thus reducing the possibility of hydraulic fluid leakage.

The present invention additionally incorporates a retarding valve in which the restricted flow is around the exterior of the valve instead of through the valve as previously done. The small, easily clogged restriction through the valve is thus obviated. Wear on the valve from the valve seat is also obviated, thus permitting a valve construction from plastic rather than more expensive materials.

The details as well as other objects and advantages of the present invention appear in the accompanying specification and the drawing, in which:

FIGURE 1 is a schematic view of the throttle actuating means and its connections to the carburetor and to the accelerator foot pedal; and

FIGURE 2 is a sectional view of the housing containing the pressure sensitive member to which the throttle valve is connected, enlarged to show in detail the pressure flow retarding valve.

Referring first to FIGURE 1, the accelerator pedal or lever 10 is shown mounted on the floor board 12 of the vehicle operator's compartment. A master cylinder housing 14 contains the first pressure sensitive member 15 to

2

which accelerator pedal 10 is connected by a rod 16. A second housing or servo 18, in which is contained the second pressure sensitive member, is connected to housing 14 by a flexible hose or conduit 20. Housing 18 is secured to the carburetor 22 by a bracket 24.

As shown in FIGURE 2, the second pressure sensitive member or diaphragm 26 is retained in housing 18. A cup-shaped member 28 is secured to diaphragm 26. Abutting member 28 is a plunger 30 which controls the throttle valve 32 (FIGURE 1) through a throttle lever 34 and an adjustable link 36. Plunger 30 is biased toward the position shown by a throttle return spring 38. Spring 38 acts through plunger 30 on diaphragm 26 against the force of hydraulic fluid within a chamber 40 formed by housing 18 and diaphragm 26.

By providing plunger 30 with an abutting connection to diaphragm 26, link 36 and plunger 30 may be manually moved toward the left to open the throttle valve without affecting diaphragm 26. Were diaphragm 26 to be secured to plunger 30 it would also move, creating a vacuum in chamber 40 and causing buckling of diaphragm 26. By avoiding this, the present invention promotes a longer diaphragm life.

A restricting valve 42 is supported by a member 44 within chamber 40. Member 44 is biased toward the left as viewed in the drawing by a spring 46. Valve 42 is biased by a spring 48 interposed between member 44 toward a reduced portion 50 of conduit 20.

As accelerator pedal 10 is depressed, the pressure of hydraulic fluid against the first pressure sensitive member 15 is increased, causing the hydraulic fluid to flow out of housing 14 and through conduit 20 to chamber 40. Valve 42 is pressed back against spring 48 and offers no obstruction to the flow of fluid into chamber 40. Openings 52 in an internal extension 54 of conduit 20 and openings 56 in member 44 permit free circulation of hydraulic fluid within chamber 40. (Extension 54 also serves as a guide for member 44.) The flow of fluid into chamber 40 increases the pressure against the diaphragm 26 and causes movement of diaphragm 26 toward the left against plunger 30 and the biasing action of spring 38, thereby opening throttle valve 32. When accelerator pedal 10 is released, the pressure of the first pressure sensitive member on the hydraulic fluid is reduced. Hydraulic fluid then flows into housing 14 from conduit 20 and chamber 40 because of the biasing action of spring 38 on diaphragm 26. The flow of fluid from chamber 40 reduces the pressure against the right side of diaphragm 26, and diaphragm 26 and plunger 30 are moved toward the right by spring 38, beginning to close throttle valve 32.

As diaphragm 26 moves toward the right, it abuts against member 44, moving member 44 against spring 46. As member 44 moves toward the right, valve 42 enters reduced portion 50 of conduit 20 and restricts the flow of hydraulic fluid therethrough to the annular clearance formed by the head of valve 42 and portion 50. The movement of member 26 and the return of closure 32 is thereby slowed.

Recalling that prior to the time valve 42 restricts portion 50 of conduit 20 no restriction is presented to the flow of fluid from chamber 40, that valve 42 is pressed back against spring 48 by displacement of the fluid from conduit 20 to chamber 40 during initial throttle valve opening and offers no obstruction to the flow of fluid into chamber 40, and that diaphragm 26, member 44, and valve 42 are all displaced to the left during greater throttle valve opening, it will be appreciated that valve 42 offers a restriction to the displacement of hydraulic fluid only during the final closing movement of throttle valve 32. This reduces the rate at which throttle valve 32 closes and reduces the tendency of the engine to stall.

It should also be emphasized that the closing rate or final retardation of throttle 32 can be calibrated or modulated to obtain the desired closing characteristic by varying the taper or formation of the inner surface of portion 50 or end of valve 42 or both.

We claim:

1. An actuator for an internal combustion engine throttle valve comprising conduit means adapted to contain a fluid through which pressure variations may be transmitted, movable means enclosing one end of said conduit means and adapted to be manually operated to cause pressure variations in the fluid contained therein, second movable means enclosing the other end of said conduit means and adapted to be connected to the throttle valve to cause movement of the throttle valve in response to fluid pressure variations in said conduit means, and valve means supported in said conduit means and locatable by the displacement of the fluid therethrough to allow relatively unrestricted fluid displacement in a throttle valve opening direction and relatively unrestricted fluid displacement in a throttle valve closing direction during predetermined movement of said second movable means in a throttle valve closing direction and relatively restricted fluid displacement after predetermined movement of said second movable means in a throttle valve closing direction to thereby lower the rate of throttle valve closing after predetermined closure thereof, said conduit means having reduced and enlarged portions, said valve means comprising a member adapted to be located in said enlarged portion of said conduit means to allow relatively unrestricted fluid displacement around said member and to be located in said reduced portion of said conduit means to cause relatively restricted fluid displacement around said member.

2. The actuator of claim 1 which further includes means biasing said member to locate said member in said reduced portion of said conduit means to restrict fluid displacement in a throttle valve closing direction.

3. The actuator of claim 2 which further includes other means adapted to support said valve means and locate said member of said valve means and means biasing said other means to locate said member in said enlarged portion of said conduit means, said other means abutting said second movable means and being movable by movement of said second movable means in a throttle valve closing direction after predetermined movement of said second movable means in a throttle valve closing direction to locate said member in said reduced portion of said conduit means to restrict fluid displacement in a throttle valve closing direction.

4. Means for controlling opening and closing movement of an internal combustion engine throttle valve comprising a member adapted to be connected to the throttle valve to control movement thereof, means biasing said member in a throttle valve closing direction, a servo having a flexible diaphragm abutting against said member and responsive to pressure increases to move said member in a throttle valve opening direction, a master cylinder having movable means adapted to be manually operated to cause pressure variations, a fluid-containing conduit connecting said master cylinder and said servo for transmitting pressure variations from said movable means to said diaphragm, valve means associated with said servo operable by the displacement of the fluid to allow relatively unrestricted fluid displacement in a throttle valve opening direction and relatively unrestricted fluid displacement in a throttle valve closing direction during predetermined movement of said diaphragm in a throttle valve closing direction and relatively restricted fluid displacement after predetermined movement of said diaphragm in a throttle valve closing direction to thereby lower the rate of throttle valve closing after predetermined closure thereof, said conduit having a reduced portion, said valve means comprising an associated valve member adapted to be located out of said reduced portion of said conduit to allow relatively unrestricted fluid displacement and to be located in said reduced portion of said conduit to cause relatively restricted fluid displacement in a throttle valve closing direction, and means biasing said valve member to locate said valve member in said reduced portion of said conduit, supporting means adapted to support and locate said valve member, and means biasing said supporting means to locate said valve member out of said reduced portion of said conduit, said supporting means being movable by movement of said diaphragm in the throttle valve closing direction after predetermined movement of said diaphragm in a throttle valve closing direction so as to locate said valve member in said reduced portion of said conduit.
